UNITED STATES PATENT OFFICE

PAUL D. WRIGHT, DECEASED, LATE OF EDGEWOOD, PENNSYLVANIA, BY OLIVE PAULIN
WRIGHT, EXECUTRIX, OF EDGEWOOD, PENNSYLVANIA

TUYÈRE

Application filed April 18, 1930. Serial No. 445,401.

This invention relates to tuyères for blast furnaces of the fluid or water cooled type having the nose of the tuyère protected by a covering of refractory material.

5 In the drawings:

Figure 1 is a central longitudinal sectional view of the improved tuyère.

Figure 1^a is a view in end elevation thereof.

Figures 2 and 2^a are views similar to Figures 1 and 1^a of a slight modification in structure.

The reference character A generally designates the metal body of the tuyère having an outer wall 5, inner wall 6 and end walls 7 and 7^a, a chamber 8 being thus provided for the circulation of a cooling fluid, most generally water.

The inner wall 6 is extended, as at 6^a, beyond the forward end wall 7^a and at its extreme forward end said wall 6 is preferably formed with a peripheral flange 6^b. This inner wall extension 6^a is provided with annular reenforcing members 9 which may be in the form of circumferential flanges, bosses 25 or like projections, and the refractory material 10 is applied over said extension 6^a and the members 9 which will thus become embedded therein.

These members 9 not only serve to reenforce the refractory material but transmit into the body thereof the cooling effect of the water, to thus lengthen the life of the tuyère nose by maintaining the refractory material at a reduced temperature when the 35 tuyère is installed and in operation.

The forward extremity of the outer wall 5 is recessed as at 5^a, to provide a catch for the one extremity of a cap 11, preferably of sheet metal. It will be understood that the 40 recessed portion 5^a may be an annular recess or a series of recesses, as desired, and likewise the extremity of the metal cap may be formed with an annular flange or a series of inwardly projecting bosses.

45 In the preferred form of the tuyère, the

metal cap 11 has its forward extremity bent over the forward end of the refractory material, as at 11^a, to assist in protecting the said material particularly during handling and installation at the furnace.

In the modified form of the tuyère as shown in Figs. 2 and 2^a, the metal cap 11 is more simple in construction, the forward extremity thereof being straight and not bent over the refractory material as in Figs. 1 and 1^a.

The end wall 7 is provided with a water inlet 12 and outlet 12^a, to provide for the introduction and circulation of cooling water in the chamber 8.

The simplicity in construction of the improved tuyère will be obvious. The metal body A may be cast in one piece and the refractory material applied over the extension 6^a and reenforcing and cooling members 9. The metal cap 11 may then be forced into position over the nose, and the tuyère is ready for installation.

What is claimed as new is:

1. A blast furnace tuyère comprising a metal body having outer, inner and end walls forming a water-circulation chamber therebetween, the inner wall having an integral extension beyond the forward end wall, said extension having a plurality of metal projections thereon, a refractory material applied over said extension so as to embed said projections, the outer wall of said body having a circumferential groove adjacent its forward end, and an outer sleeve-like cap covering said refractory material, the rear end of said cap being bent into said groove in the outer wall of said body and the forward end of said cap being bent over the forward end of said refractory material, to protect said material during handling and installing.

2. A blast furnace tuyère comprising a metal body having outer, inner and end walls forming a water-circulation chamber therebetween, the inner wall having an integral

extension beyond the forward end wall, said extension having a plurality of metal projections thereon, a refractory material applied over said extension so as to embed said projections, the outer wall of said body having a circumferential groove adjacent its forward end, and an outer sleeve-like cap covering said refractory material, the rear end of said cap being bent into the groove in the outer wall of said body.

In testimony whereof, I have hereunto set my hand.

OLIVE PAULIN WRIGHT,
Executrix of the Estate of Paul D. Wright,
15 Deceased.
